Specification of Letters Patent. Patented July 23, 1918.

Application filed April 7, 1917. Serial No. 160,479.

To all whom it may concern:

Be it known that I, FRANK B. NIHART, a citizen of the United States, residing at Bay Minette, in the county of Baldwin and State 5 of Alabama, have invented new and useful Improvements in Stationery-Holders, of which the following is a specification.

This invention relates to paper holders and is especially adapted for use in connection with typewriters for holding office stationery in convenient position.

The object of the present invention is to provide a cheap and attractive receptacle which may be removably secured to a typewriter in a convenient position, the said receptacle being adapted to hold stationery of various kinds, such as letter heads, bill heads, envelopes and the like.

A further object of the invention is to construct a device of this kind in which the weight of the paper or stationery contained therein will be located directly over the supports, in order that the device may be secured in position upon a typewriter in a manner not to interfere or obstruct the operation of the same and at the same time will be located within convenient reach.

With these and other objects in view, the invention consists in the following novel combination and arrangement of parts herein more fully described and illustrated in the accompanying drawings, in which—

Figure 1 is a side elevation of a paper holder constructed in accordance with the present invention and illustrated as applied to a typewriter, said typewriter being indicated in outline by dotted lines.

Fig. 2 is a perspective view of the paper holder detached from the typewriter.

Fig. 3 is a central vertical longitudinal sectional view through the device.

Fig. 4 is a transverse sectional view of the same.

Referring in detail to the drawings, a typewriter is indicated generally at A and a portion to which the supports of the paper holder are secured is indicated at B.

The device itself which constitutes the present invention includes a receptacle 10 and the supports 11.

The receptacle is preferably formed with a wire frame and includes the sides 12, between which are provided a plurality of

compartments 13, 14, and 15, which are preferably rectangular in plan view and are of 55 a convenient size to receive various kinds of printed stationery. The front 16 of the receptacle is open so as to provide an open front end for each of the various compartments. The rear portion of these compartments is closed as indicated at 17, so that the various sizes of paper are so arranged 60 as to place the weight at or near the front end of the receptacle.

The supports 11 are located beneath this 65 end of the receptacle, these supports comprising the permanently secured sections 18, which extend along beneath the body of the receptacle and are formed at their front ends with downwardly extending portions 19. 70 These portions 19 are adapted to be removably secured within sockets 20 formed in the upper ends of each of the removable sections 21 of the supports. The lower ends of the sections 21 are provided with parallel 75 engaging members 22, which are adapted to take over the portion B of the typewriter and to be secured thereon by means of the set screws 23. In order to hold the sections 21 in their proper spaced relation, there are 80 provided angularly arranged brace rods 24, which are secured to each of the said sections and to one another as shown at 25.

By reference to Fig. 1 of the drawings it will be seen that the device is secured to a 85 typewriter within convenient reach of the operator and that the compartments of the receptacle are so arranged as to place the majority of the weight of its contents close to the supports 11, so as to relieve the weight 90 from the unsupported end of the compartments. By forming the supports into the removably secured sections, it is possible to remove the holder from the machine without detaching the sections 21, so that the said 95 holder may be carried to the stationery room to permit of it being conveniently filled, or if desired the entire device may be removed from the machine by loosening the screws 23.

It is believed that from the foregoing description taken in connection with the accompanying drawings the construction and advantages of the invention will be apparent. The right is reserved to make such changes 105 in the form and proportion thereof as will fall within the scope of the appended claim,

Having described the invention, what is claimed is:

A stationery holder comprising in combination a receptacle, said receptacle including a plurality of horizontally disposed compartments arranged one above the other and open at one end, said compartments being of

various depths and having their open ends arranged in vertical alinement and a support secured to said receptacle at the open end thereof, so as to dispose the greatest weight near said support. 10

In testimony whereof I affix my signature.
FRANK B. NIHART.

Copies of this patent may be obtained for five cents each, by addressing the "Commissioner of Patents, Washington, D. C."
